UNITED STATES PATENT OFFICE.

CHARLES EDWARD DEVINE, OF PLATTSBURG, NEW YORK, ASSIGNOR OF ONE-HALF TO CHARLES PAXTON, OF SAME PLACE.

THREAD-RELEASER FOR SEWING-MACHINES.

SPECIFICATION forming part of Letters Patent No. 327,925, dated October 6, 1885.

Application filed March 12, 1885. Serial No. 158,604. (No model.)

To all whom it may concern:

Be it known that I, CHARLES EDWARD DEVINE, of Plattsburg, in the county of Clinton and State of New York, have invented certain new and useful Improvements in Thread-
Releasers for Sewing-Machines; and I do hereby declare that the following is a full, clear, and exact description of the same.

My invention is applicable to those machines which are furnished with "plate" tension-regulators; and it consists in means by which the operation of the presser-bar lifter will simultaneously raise the presser-foot and release the top thread from tension, thus giving to the operator the use of both hands to take goods from under the presser-foot by doing away with the necessity, when the presser-foot is raised, of the operator keeping one hand on a tension-liberator or of pulling some slack thread through tension on the top of machine-arm, the omission of this latter often causing the breaking of the thread or the bending or breaking of the needles. The chance of this is entirely obviated by my device, which also always keeps the thread taut, preventing slack thread when the operator begins to sew.

For full comprehension of my invention reference must be had to the annexed drawings, in which Figure 1 shows a side view of part of the arm, face-plate, &c., of a sewing-machine to which my invention has been applied, with the parts in the position they occupy while sewing is being done; Fig. 2, a similar view showing the tension released; and Fig. 3, a front view of face-plate, &c.

Similar letters of reference indicate like parts.

A is the arm, A' the head, B the face-plate, and C the presser-bar, of a sewing-machine, all

these being of any ordinary and suitable construction.

D is the presser-bar lifter, acting, as usual, against a stud, c, on the presser-bar.

E is the tension leaf, plate, or disk, secured to projection on the arm A by set-screw E', which regulates the pressure.

F is a bent lever, pivoted at f to the arm, and having a turned-up end, F', which is acted upon by the presser-bar lifter D.

G is a link connected to F by its bent end at the obliquely-cut recess F'', and being turned and secured to the plate H, which is provided with ears h, pivoted to a projection from A.

The operation of my invention is as follows: When the operator desires to remove the goods from under the presser-foot, she raises the presser-bar lifter D, and this simultaneously acts upon the presser-bar C and the lever F, and through G upon the plate H, with drawing it from the tension-plate E at the point e, where the thread passes through the plate, thus freeing the tension and allowing the thread to be drawn through. It must be understood that any other combination of equivalent elements may be used to transmit the action of the presser-bar lifter to the tension device to free thread from same.

What I claim is as follows:

In a sewing-machine, the combination, with the presser-bar lifter, of a pivoted bell-crank lever with turned-up end, connected with the lower plate of the tension device, and operated directly by the presser-bar lifter to loosen the tension simultaneously with the raising of the presser-bar, substantially as described.

CHARLES EDWARD DEVINE.

CHARLES HENRY BOOTH.

Correction in Letters Patent No. 327,925.

It is hereby certified that the name of the assignee of one-half interest in Letters Patent No. 327,925, granted October 6, 1885, upon the application of Charles Edward Divine, for an improvement in "Thread-Releaseers for Sewing-Machines," was erroneously written and printed "Charles Paxton;" that the name of said assignee should have been written and printed *Charles Parton*; and that the said Letters Patent should be read with this correction therein that the same may conform to the record of the case in the Patent Office.

Signed, countersigned, and sealed this 24th day of November, A. D. 1885.

[SEAL.]

H. L. MULDROW,
Acting Secretary of the Interior.

Countersigned:

M. V. MONTGOMERY,
Commissioner of Patents.
